Primary Examiner — April Rivas(74) *Attorney, Agent, or Firm* — RMCK Law Group, PLC(57) **CLAIM**

The ornamental design for a trunk as shown and described.

DESCRIPTION

FIG. 1 is an elevated, perspective front view of a first embodiment of a trunk in accordance with the present teachings;

FIG. 2 is a front view of the trunk of FIG. 1;
FIG. 3 is a left side view of the trunk of FIG. 1;
FIG. 4 is a right side view of the trunk of FIG. 1;
FIG. 5 is a rear view of the trunk of FIG. 1;
FIG. 6 is a top view of the trunk of FIG. 1;
FIG. 7 is a bottom view of the trunk of FIG. 1;
FIG. 8 is a first elevated, perspective rear view of the trunk of FIG. 1; and,
FIG. 9 is a second elevated, perspective rear view of the trunk of FIG. 1.

The broken lines shown herein illustrate portions of the trunk and form no part of the claimed design.
